UNITED STATES PATENT OFFICE.

OSCAR J. RENSHAW, OF LANGELLS VALLEY, OREGON.

RIFLE TURBINE.

Application filed November 19, 1921. Serial No. 516,465.

To all whom it may concern:

Be it known that I, OSCAR J. RENSHAW, a citizen of the United States, residing at Langells Valley, in the county of 5 Klamath and State of Oregon, have invented certain new and useful Improvements in Rifle Turbines, of which the following is a specification, reference being had therein to the accompanying drawings.

10 This invention relates to a rifle turbine, and has for its object the construction of a simple and efficient mechanism utilizing steam for rotating a piston, which piston is provided with peculiarly-constructed grooves, 15 and which mechanism also includes an efficient valve mechanism for enabling the operation of the mechanism in an efficient manner.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a vertical, sectional view of a mechanism constructed in accordance with the present invention.

30 Figure 2 is a sectional view, taken on line 2—2, Fig. 1, and looking in the direction of the arrows.

Figure 3 is a top, plan view of the rotary piston.

35 Figure 4 is a section, taken on line 4—4, Fig. 3, and looking in the direction of the arrows.

Figure 5 is a longitudinal, sectional view of another embodiment of the present invention.

40 Referring to the drawings by numerals, 1 designates the base structure or foundation upon which is mounted the primary casing 2. Suitable exhaust pipes 3 extend through the foundation 1 and communicate at their inner ends with the bottom of the casing 2. A rotary piston 4 is mounted within the casing 2, and extending through the piston 4 is a driving shaft 5. It is to be noted that 45 the piston 4 is conical in shape. The lower end of the shaft 5 is provided with a ball 6, and this ball is mounted in bearing 7. A suitable packing 8 makes a tight joint around shaft 5, contiguous to the bearing 7, 50 preventing any leaking of steam or liquid around the shaft 5.

The conical piston 4 is provided in its top with a circular groove 9, Fig. 3, and with horizontal, V-shaped grooves 10 (V-shaped in cross section) which grooves 10 open at 60 their outer ends in spiral grooves 11; grooves 11 extend around the side of the rotary piston 4.

Inlet pipes 12 communicate at their inner ends with grooves 10, Fig. 1; this communication with grooves 10 is accomplished through the medium of a funnel-like construction 13 at the inner end of each inlet pipe 12, Figs. 1 and 4.

A valve seat 14 is formed in the inner 70 end of each pipe 12, and a sliding valve 15 is in each pipe 12 and is adapted to normally seat upon valve seat 14, Fig. 1. A valve stem 16 is attached to each valve 15, and the outer end of the stem 16 extends beyond pipe 12. The outer end of each stem 16 is pivotally connected, at 17, to auxiliary 75 rocker-arms 18; the rocker-arms 18 are pivotally mounted, at 19, upon brackets 20. An auxiliary casing 21 is formed upon 80 each inlet pipe 12 and a sliding piston 22 is in each casing 21. A rod 23 is connected to each piston 22, the outer end of the rod is pivotally connected to the outer end of the auxiliary rocker-arm 85 18. A valve chamber 24 is provided with two hollow extensions 25, communicating with the auxiliary casing 21; in valve chamber 24 is a pair of pistons 26 fastened to valve stem 27. A by-pass 28 communicates 90 with pipe 12 and with the valve chamber 24. Primary rocker-arms 29 are pivotally mounted, at 30, upon the frame 31 and their outer ends are pivotally connected, at 32, to the outer ends of valve stems 27. The inner 95 ends of the primary rocker-arms 29 are pivotally connected to the collar 33, which collar 33 is slidably mounted upon the primary shaft 5; this collar 33 is a part of the governor device 34, which governor device is 100 fastened, at 35, to shaft 5.

A dynamo or any suitably driven machinery is adapted to be carried by frame 31, at 36; the driving shaft 5 extends up into the casing 26 and is connected by any ordinary 105 means to the machinery to be driven by my mechanism.

It is to be understood that upon live steam being discharged through the inlet pipes 12 into casing 2 that the rotary piston will be 110 actuated (rotated) causing the driving shaft 5 to operate the governor device 34, and the

faster the shaft 5 rotates the greater the governor device 34 will be operated to pull down on the inner ends of the rocker arms 29, causing the raising of valve stems 27 and, consequently, permitting live steam to pass in the lower hollow extensions 25, whereupon the pistons 22 will be shoved upwardly partly closing or entirely closing valves 15 as the speed increases; upon the speed of the mechanism decreasing the valve mechanism will be automatically operated to permit the opening of valves 15, or a greater upward movement of said valves from their seats 14, allowing sufficient steam to enter the casing 2 and act upon the rotary piston 4 to maintain the desired speed fixed or governed by the governor device 34.

In the embodiment shown in Fig. 5, I have shown what might be styled a "horizontal mechanism," whereas in Fig. 1 I have shown a "vertical mechanism"; in Fig. 5 the conical piston 4 is in a horizontal position, within the casing 2. The flow of steam from the casing 2 through inlet pipes 12^a is controlled by governing mechanism 37.

When this turbine is in use the steam is turned on and passes through the pipes 12 into the groove 9 in the smaller end of the rotor 4. From the groove 9 the steam passes through the radiating grooves 10 into the grooves 11 which extend spirally about the sides of the rotor until it reaches the larger end of the rotor and passes out of the casing through the outlet pipes 3. While the steam is passing through the spiral grooves 11 from the small end towards the large end of the casing and expanding during its movement it will act against the walls of the grooves and this will set up an action which will cause the rotor to be turned towards the left in Figure 1. The steam will be in operative engagement with the walls of the grooves during its entire movement to the large end of the casing and there will be no abrupt rewinds. Therefore the maximum amount of power will be obtained from the steam. The governor controls the valves and opens and closes them as the speed of rotation of the rotor and shaft changes and therefore the proper amount of steam will be fed into the grooves.

While I have described the preferred embodiments of my invention, and have illustrated the same in the accompanying drawings, certain minor changes or alterations may appear to one skilled in the art to

which this invention relates, during the extensive manufacture of the same and I, therefore, reserve the right to make such alterations or changes as shall fairly fall within the scope of the appended claims.

What I claim is:

1. In a mechanism of the class described, the combination with a casing, of a rotary piston provided with a driving shaft mounted in said casing, said piston provided in its side with a spiral groove and on one end with a circular groove and with a groove V-shaped in cross section communicating with said circular groove and said spiral groove, and means for supplying steam to said grooves of said piston.

2. In a mechanism of the class described, the combination with a conical casing, of a conical rotary piston in said casing provided with a driving shaft, said piston provided with a plurality of spiral grooves in its side and on one end with a circular groove and with a plurality of grooves extending radially of the end and opening into said circular groove and said spiral grooves, and valved means for supplying steam to said grooves.

3. In a mechanism of the class described, the combination with a casing, of a rotary piston provided with a driving shaft in said casing, said piston provided with an endless groove extending radially of the end and with a spiral groove in its side communicating with the first-mentioned groove, said casing provided with a funnel-like construction opening upon the first-mentioned groove, and valved means for supplying steam through said funnel-like construction and to said grooves.

4. In a mechanism of the class described, the combination with a casing, of a rotary piston in said casing, said piston provided with grooves in its sides and with a circular groove in one end, said piston provided with a plurality of grooves in its end extending radially of the end of the piston and communicating at their inner ends with said circular groove and at their outer ends with the grooves in the side of the piston, and valved means connected to the casing and adapted to supply steam to said grooves of the piston.

In testimony whereof I hereunto affix my signature.

OSCAR J. RENSHAW.
